[57] CLAIM

The ornamental design for an irrigation control console, as shown and described.

DESCRIPTION

FIG. 1 is a perspective view of an irrigation control console showing my new design;

FIG. 2 is a side elevational view, the opposite side being a mirror image of the side shown;

FIG. 3 is a front elevational view;

FIG. 4 is a top plan view; and

FIG. 5 is a rear elevational view.
